UNITED STATES PATENT OFFICE.

MICHAEL H. MCKENNA, OF CLEVELAND, OHIO.

MACHINE FOR BENDING METAL BARS.

1,277,235.

Specification of Letters Patent. Patented Aug. 27, 1918.

Application filed October 13, 1917. Serial No. 196,356.

To all whom it may concern:

Be it known that I, MICHAEL H. MCKENNA, a citizen of the United States, residing at Cleveland, in the county of Cuyahoga and State of Ohio, have invented certain new and useful Improvements in Machines for Bending Metal Bars, of which the following is a specification.

In my pending application Ser. No. 196,355 10 there is disclosed a machine for bending bars or the like characterized by the use of an oscillating shaft carrying a bending arm, and a drive gear which may be clutched or latched to the shaft by an arm projecting 15 therefrom, in order to turn the latter, the catch being automatically released at the end of the stroke.

The present invention is a modification of or improvement on a machine shown in 20 said application, the object being to provide improved means for swinging the shaft back to original position after each stroke, upon the release of the automatic catch. Further features of the present invention relate 25 to the devices for holding and bending the work, said devices including a disk mounted on the shaft, instead of the arm referred to.

In the accompanying drawings,

30 Figure 1 is a plan of the machine in one position.

Fig. 2 is a similar view in another position.

Fig. 3 is a side elevation.

35 Fig. 4 is a section on the line 4—4 of Fig. 3.

Fig. 5 is a section on the line 5—5 of Fig. 1.

Fig. 6 is a partial section on the line 6—6 40 of Fig. 1.

Fig. 7 is a detail of the attaching device for the spring which returns the shaft.

In the drawings, 1 indicates the base of the machine, 2 a bed plate thereon, 3 a table 45 supported by posts 4, 5 a vertical shaft which extends through the table and is supported in a step bearing 6, 7 an upper bearing for the shaft and 8 a gear loose on the shaft.

50 Fixed to the shaft 5 is an arm 10 carrying a pivoted latch 14 mounted on a pivot 12 at the end of the arm 10 and provided with the hook 16 adapted to engage one of a series of lugs 9 on the wheel 8. This latch has a 55 handle 17 which travels in a slot 18 in the

table. The latch is thrown in by hand and is thrown out by striking an adjustable stop block 46. The foregoing parts are more fully described in the application above referred to. 60

The wheel 8 is driven constantly by a pinion 23 on a shaft 22 which carries a worm gear 50 driven by a worm 51 from an electric motor 34, the worm being supported in bearings 52 and some of the gears being enclosed by a casing 58. The shaft 22 is supported in bearings at the top and bottom on the plates 2 and 3. 65

By engaging the latch with one of the lugs 9 the bending shaft 5 is turned in one direction, until the latch is released by the handle 17 striking the block 46. To turn the shaft to original position I provide a coiled spring 56 connected to one of the posts 4 and by a chain 55 to a fixture on the shaft 5. 70 The spring may be adjusted by a nut 57. The fixture referred to is indicated as a whole at 54 in Fig. 4 and consists (see Fig. 7) of a split collar 69 which matches with a removable section 71 having a key way 72 by 75 which it may be keyed to the shaft. The collar sections are fastened together by a pin inserted through holes 76 in the part 69 and a hole 73 in the part 71. The collar has a groove 70 for the chain and a hole 75 in 80 a lug 74 to receive a pin to connect the end of the chain. 85

Mounted at the top of the shaft 5, above the table 3, is a disk 59 having a series of slots 61 and 62 to receive a pin 60 by which a bending roller 41 is adjustably attached to the disk. Two sets of slots 61 and 62 are provided to accommodate either right or left hand work. Mounted on the extreme upper end of the shaft 5 is a roller or former 42 90 around which the work is bent. 63 is a block secured to the table 3 and supporting an abutment block 65 adjustable by bolts 66 to desired position to accommodate different kinds of work. When used as a left hand 100 machine the blocks 63 and 65 may be reversed and secured by bolts in the holes 68, the bender 41 being then transferred to one of the slots 62. 105

In the operation of the machine, the bar to be bent is placed against the block 65 and between the former 42 and bender 41, as shown in Fig. 1. The clutch 16 is then engaged by swinging the handle 17 and the shaft 5 and disk 59 are swung around, bend- 110

ing the bar around the former 42 as shown in Fig. 2. The stop 46 being set at the desired place will throw out the latch or clutch when the bend is completed, and the spring 56, being then extended, will return the shaft and the disk carried thereby to original position for the next operation. The disk 59 is provided at its rim with a stop block 67 which strikes the block 63 when the 10 disk reaches original position. The wheel 8 rotates continuously and by the means described bars can be bent as rapidly as they can be placed in and removed from the machine, the clutch being engaged by hand 15 at the beginning of each operation and automatically released and the bender returned at the end of each operation.

Copies of this patent may be obtained for five cents each, by addressing the "Commissioner of Patents, Washington, D. C."

I claim:

In a metal bending machine, the combination of an oscillatable bender shaft, means including a clutch to turn the shaft one way, means to release the clutch at the end of the stroke, and means to automatically return the shaft to original position after the clutch is released said means including a spring, and a collar on the shaft to which the spring is connected, said collar being reversible to connect the spring at either side of the shaft. 20 25

In testimony whereof, I do affix my signature in presence of two witnesses.

MICHAEL H. McKENNA.

Witnesses:

JOHN A. BOMMHARDT,
G. V. ROSENBERG.
